CLAIM

The ornamental design for a camera unit as shown and described.

DESCRIPTION

FIG. 1 is a top and front perspective view of a camera unit showing our new design;

FIG. 2 is a bottom and rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines depict portions of the camera unit that form no part of the claimed design. The dash-dot broken lines denote the boundary of the claim and form no part of the claimed design.
